(57) **CLAIM**

The ornamental design for an gap covering device for aircraft wall panels, as shown and described.

DESCRIPTION

FIG. 1 is a bottom, front, right side perspective view of a gap covering device for aircraft wall panels showing our new design in use.

FIG. 2 is a front elevation view taken along line 2-2 in FIG. 1.

FIG. 3 is a top view taken along line 3-3 in FIG. 1.

FIG. 4 is a rear bottom perspective view of the gap covering device of FIG. 1.

FIG. 5 is a cross-sectional view taken along line 5-5 in FIG. 4.

FIG. 6 is a rear top perspective in cross-section along line 5-5 in FIG. 4.

FIG. 7 is a front perspective view of the gap covering device of FIG. 1; and,

FIG. 8 is a perspective view of the gap covering device of FIG. 1 in an airplane cabin shown in broken lines.

The broken lines in the drawings showing a portion of aircraft wall panels illustrate environmental structure and form no part of the claimed design. Also, the non-shown portion of the gap covering device for aircraft wall panels forms no part of the claimed design.
